SAIL BOAT HULL

Stephen M. Taylor, 2337 Nottingham Court,
Minneapolis, Minn.

Filed Nov. 18, 1963, Ser. No. 77,456

Term of patent 14 years

(Cl. D71—1)

FIG. 1 is a view in top plan of a sail boat hull showing my new design;

FIG. 2 is a view in side elevation thereof, the opposite side being a mirror image thereof;

FIG. 3 is a view in bottom plan thereof;

FIG. 4 is a view in front elevation thereof;

FIG. 5 is a view in rear elevation thereof; and

FIG. 6 is a view in longitudinal section taken along the line 6—6 of FIG. 1.

I claim:

The ornamental design for a sail boat hull, as shown and described.
